PROCESS OF REFINING OILS

Benjamin H. Thurman, Bronxville, N. Y., assignor
to Refining, Inc., Reno, Nev., a corporation of
Nevada

Application June 22, 1938, Serial No. 215,251

8 Claims. (Cl. 260—425)

This invention relates to a process of refining animal and vegetable oils, and more particularly to a low temperature process in which relatively concentrated alkali refining solutions are employed.

An object of the present invention is to provide an improved process of alkali refining animal and vegetable oils by which the refining losses are reduced.

Another object of the invention is to provide a low temperature alkali refining process for the refining of animal and vegetable oils in which concentrated alkali refining solutions are employed in order to facilitate centrifugal separation of soap stock from oil at relatively low temperatures.

A further object of the invention is to provide a rapid process of refining animal and vegetable oils in which relatively concentrated alkali refining reagents are employed and a clean separation of the resultant soap stock from the refined oil effected.

A still further object of the invention is to provide a continuous and rapid process of refining animal and vegetable oils in which low temperatures and concentrated alkali refining solutions are employed in order to reduce refining losses.

Other objects and advantages of the invention will appear in the following description of the preferred process, which will be described in conjunction with the attached drawing, of which:

Figure 1 is a schematic diagram of an apparatus capable of carrying out the process of the present invention; and

Figure 2 is a similar view of a modification of a portion of the apparatus.

Animal and vegetable oils are at present refined either in batch or continuous processes by adding an excess of an alkaline refining reagent, usually a caustic soda solution, in proportioned amounts, to the oil so as to form soap stock which is separated from the oil by difference in specific gravity. In these prior art processes, a relatively dilute refining reagent is employed. When such a refining solution is mixed with the oil, a difficulty separable emulsion, apparently of the water and oil type, tends to form and does form if the mixing is performed at relatively low temperature, for example, temperatures below 100° F. This emulsion is broken by the employment of elevated temperatures, for example, temperatures between 100 and 160° F., and usually between 120 and 160° F., so that soap stock can be separated from the oil. In batch operations this

heating is performed subsequent to mixing and the soap stock allowed to settle from the oil. In continuous operations, which have largely superseded batch operations, the elevated temperature necessary for effective separation is obtained either by heating the oil in flow prior to mixing or by heating the mixture in flow, and separation is effected by continuously centrifugally separating the soap stock from the oil. In these processes the concentration of the refining solution ranges from approximately 12° Bé. to 20° Bé. The lower range is employed for high quality low free fatty acid oils, for example, hot pressed cottonseed oil having less than 1.5% free fatty acids, while the upper range is employed for low quality cold pressed oils having extremely large amounts of free fatty acids. The strength of refining solution for the usual run of oils seldom exceeds 20° Bé. For example, for cottonseed oils ordinarily encountered and containing 3% or less free fatty acid, the strength of refining reagents ranges between approximately 12° and 16° Bé.

In accordance with the present invention, I have found that a rapid process, and preferably a continuous process resulting in lowered refining losses, can be carried on at low temperatures, for example, 70° to 90° F., with refining solutions ranging between 20 and 50° Bé. In the present process with high quality low free fatty acid oils, for example, those having below 1.5% free fatty acids, it is sometimes possible to employ refining solutions as low as 20° Bé., in contrast with 12° Bé. solutions for prior processes, but more highly concentrated solutions are preferable, and the concentration will run as high as 50° Bé. for oils containing an excessive amount of free fatty acids, in contrast with a maximum of 20° Bé. for prior processes.

Adequate refining of neutral oil can be effected by the known refining processes above discussed. However, refining processes are always attended with substantial refining losses. These losses are made up of (1) loss due to neutralization of free fatty acids and precipitation and removal of gums, (2) losses due to saponification of neutral oil, and (3) losses due to entrainment of neutral oil in the soap stock. The first of these refining losses is unavoidable. The known continuous processes result in lower losses due to saponification and entrainment of neutral oil than conventional batch processes but the present process still further reduces these losses, thus resulting in savings in over-all refining losses.

Several factors affect the amount of neutral oil saponified. Saponification of neutral oil goes

forward at a faster rate if the refining reagent or soap stock containing excess refining reagent is emulsified with and thereby is extremely close contact with the neutral oil. The rate of saponification of neutral oil also increases with temperature, either in the presence or absence of an emulsion. The amount of neutral oil saponified also increases with time. It has also been found that the rate of neutral oil saponification for a short time after mixing increases with decrease in concentration of the refining reagent. In accordance with the present invention, no emulsion is formed during mixing, or, if formed, it is immediately broken; a low temperature is maintained throughout the process; the resultant soap stock along with excess reagent is promptly separated from the oil; and concentrated refining solutions are employed such that saponification of neutral oil is minimized.

Entrainment of oil in the soap stock depends primarily upon the effectiveness of the separation of the soap stock from the oil. Centrifugal separation of a properly conditioned mixture, i. e. a well broken emulsion, results in much less entrainment of neutral oil than batch settling operations. Also, entrainment increases with the amount of refining solution employed. The present invention contemplates such centrifugal separation, and also the increased concentration of the refining solutions decreases the amount of refining solution necessarily mixed with the oil to neutralize the free fatty acids and provide the proper excess found to be necessary for color reduction. Thus the present invention also markedly reduces the losses due to entrainment even over known continuous refining processes.

The concentration of the refining solution employed in accordance with the present invention should be sufficient to produce almost immediate breaking of the emulsion at the low temperatures contemplated. If the refining solution is too concentrated, however, not only is the emulsion broken but the soap tends to separate from the water and excess refining reagent by a salting out action. Thus, if too concentrated refining solutions are employed, the soap stock stratifies in the centrifugal separator into two layers, a soap layer and a water or nigre layer, and this effect increases with increase of concentration. The soap layer mixes with a large quantity of neutral oil, and the nigre with a small amount of soap is discharged as the heavy effluent, while a large proportion of the soap is discharged with the oil as the lighter effluent, such that effective separation between soap and oil is not produced.

The amount of stratification in the centrifugal separator has also been found to increase with the time of treatment between mixing and separation. With certain oils, for example, cotton-seed oil, which is a highly colored oil, it is desirable to provide a short period of time between the mixing and separation in order to cause the color of the refined oil to be reduced. Although neutralization of the free fatty acids occurs substantially as soon as the refining solution is mixed with the oil, reduction of color, which appears to involve an adsorption in the presence of excess alkali of coloring material by the soap stock formed during neutralization, in some cases requires an appreciable length of time. This color reduction reaction goes forward at low temperatures, and after the emulsion has been broken, but the rate of color absorption decreases with the increased concentration of lye.

By employing just sufficient concentration of refining reagent to substantially immediately break any emulsion which tends to form at the low temperatures, it has been found that, with almost all oils, the mixture may be maintained for a sufficient length of time to produce said color reduction without causing any substantial amount of stratification in the centrifugal separator. Separation operations involving settling of the soap stock from the oil are impractical, since the time required for such settling causes stratification of the soap stock and admixture of a large quantity of neutral oil with soap. With certain oils, where difficulties with stratification are encountered, if sufficient time of treatment for satisfactory color removal is provided, it has been further found that the addition of a stream of water to the stream of mixture entering the centrifuge or to the soap stock component of the mixture within the centrifuge will overcome stratification in the centrifuge, even though it would occur in the absence of added water. The water dilutes the nigre such that the concentration of excess refining reagent is reduced below that which produces stratification. Water thus added is not in contact with the mixture for sufficient time to cause any appreciable amount of emulsion to form or increase in saponification of neutral oil as is the case where the refining reagent is relatively dilute when admixed with the oil. This addition of water is not to be confused with a washing or flushing operation to wash the soap stock out of the centrifugal, as insufficient water is added for the latter purpose.

Separation is preferably accomplished in the heated centrifugal separator of the type disclosed in the patent to Clayton No. 2,100,277, granted Nov. 23, 1937. The soap stock at the temperature above mentioned will ordinarily not discharge continuously from a conventional centrifugal separator, as it is a thick viscous material which adheres to the walls of the bowl. By employing the heated centrifugal referred to, the walls of the bowl may be heated sufficiently to cause the soap stock to slip continuously along the heated surfaces of the bowl and thus be discharged continuously therefrom. It is unnecessary to employ sufficient heat to measurably increase the temperature of the oil being discharged from the centrifugal, although, in general, the average temperature of the soap stock will be somewhat raised in the centrifugal bowl.

From the above discussion it will be observed that the present process is susceptible of being carried out with either continuous mixing of streams of oil and reagent, or the oil and alkali may be mixed in such small batches that continuous centrifugal separation can be effected before substantial salting out with resultant stratification occurs. The continuous operation is preferable, as the time of treatment of the mixture between mixing and separation can be made constant for all portions of the oil and more accurately controlled and is desirably carried out in an apparatus similar to that shown in the drawing above referred to.

Referring more particularly to the drawing, a source of supply for oil to be refined is indicated as a tank 10, and a source of supply for the alkaline refining reagent is indicated as a tank 11. The tanks 10 and 11 may be provided with heat exchange coils 12 and 13, respectively, through which a heating or cooling medium may be circulated to bring the oil and alkali to the desired temperature. This temperature will range be-

tween 60 and 100° F., but usually between 70 and 90° F., and is preferably approximately 80° F. Thus no heating or cooling of the oil and alkali in the tanks 10 and 11 will be necessary except under extreme weather conditions where the tanks are exposed to atmospheric temperatures. Oil is withdrawn from the tank 10 by means of a proportioning pump 14 and delivered to a flow mixer 15. Sufficient refining solution to neutralize the free fatty acids and provide an excess for color removal is withdrawn from the tank 11 by means of a proportioning pump 16 and delivered to the mixing device 15. The proportioning pumps are shown as being driven by a variable speed motor 17 with a speed exchange device 18 positioned between the pumps so that any desired amounts and proportions of the oil and alkali may be delivered to the mixer 15. The proportioning mechanism shown is merely by way of example, and any desired proportioning mechanism capable of delivering accurately proportioned streams of oil and refining reagent to the mixing device 15 may be employed.

The mixing device 15 is preferably of the type disclosed in the copending application of Benjamin H. Thurman, Serial No. 190,673, filed Feb. 15, 1938, but any other type of efficient flow mixer such as a closed mechanical agitator may be employed in lieu thereof. In many instances, merely injecting a stream of alkali at right angles into a flowing stream of the oil is sufficient, as animal and vegetable oils containing free fatty acids mix readily with alkaline refining solutions. Neutralization of the free fatty acids occurs almost instantaneously in the mixer 15 and in the present process the alkaline refining reagent has sufficient concentration to prevent the formation of or almost immediately break any emulsion which tends to form at the temperature of mixing. Thus the mixture is almost immediately in condition for centrifugal separation, and, if no treating time for color reduction is necessary for the particular oil being treated, the mixture may be delivered through the pipe 19 directly to the continuous centrifugal separator 20.

If a short time of treatment for color reduction is necessary or desirable, the mixture may be caused to flow through one or both of the coils 21 and 22. Thus by closing the valve 23 in the pipe 19 and opening the valve 24, while at the same time maintaining the valve 25 open and the valve 27 closed, the mixture may be caused to flow through the coil 21. Then, by closing the valve 25 and opening the valve 27, the mixture may be caused to also flow through the coil 22. Such coils may provide conduits of substantial length, for example, 250 feet, such that an appreciable time may be required for passing the mixture therethrough. As a specific example, such a coil may be made of a $\frac{3}{4}$ inch pipe 250 feet in length, and the mixture pumped therethrough at a rate requiring $2\frac{1}{2}$ minutes for the mixture to pass through the coil. As many coils as necessary may be employed to produce the required treating time, which time rarely exceeds 5 minutes, and, at most, no more than 10 or 15 minutes.

Instead of employing coils such as 21 and 22 for providing time of treatment for color reduction, the mixture may be delivered into the chamber 34 of Figure 2, which chamber is preferably closed from the atmosphere, and provided with an agitator 35 rotated from any suitable source of power through a pulley 36. The

agitator 35 is rotated at a rate which is sufficient only to prevent settling of the soap stock and is insufficient to cause beating the soap stock back into the oil. The amount of mixture maintained in the chamber 35 and, therefore, the time of treatment thereof between mixing and separation can be varied by the valves 37, since the lowermost open valve 37 will determine the level of the mixture in the chamber 34.

In case it is found that appreciable quantities of soap are discharging with the neutral oil, from the centrifugal separator, a stream of water may be introduced into the pipe 19 through a pipe 28 in order to overcome the stratification of the soap stock in the centrifugal. Only a very small amount of water is required, as it is only necessary to slightly reduce the concentration of the excess refining solution in the centrifugal in order to prevent stratification. As stated above, this water may also be introduced into the bottom of the centrifugal bowl by a pipe (not shown) so as to mix only with the soap stock layer in the centrifugal.

The refined oil substantially free of soap is discharged from the centrifugal as the lighter effluent through the pipe 29 and may be subjected to the known washing and drying or bleaching steps and deodorizing steps known to the art. The soap stock discharges as the heavy effluent through a spout 30 into a soap stock receptacle 31.

As disclosed in the copending application of Benjamin H. Thurman, above referred to, steam may be supplied to the centrifugal casing by means of the pipe 32 so as to surround the bowl 35 and discharge passages thereof and cause the soap stock to continuously discharge from the centrifugal. Any condensate from the steam may be discharged through a pipe 33. A clean separation of the soap stock from the refined oil can thus be effected, and refining losses reduced even with respect to modern continuous refining processes employing elevated temperatures for breaking the emulsion.

As specific examples of refining operations in the above apparatus, a Brazilian crude cottonseed oil containing 2.8% free fatty acids was admixed with 5.9% of a 24° Bé. caustic soda solution in the mixer 15 at a temperature of 80° F. The mixture was passed through the two coils 21 and 22 and thus given a treating period for color removal of approximately 5 minutes. This mixture was then delivered directly to the centrifugal separator 20. Separation was effected with sufficient steam around the bowl 35 thereof to cause continuous discharge of the soap stock and neutral oil substantially free of soap stock discharged as the lighter effluent.

As another example, a crude cottonseed oil having a free fatty acid content of 3.5% was mixed with 4.25% of 30° Bé. lye solution at 80° F. and sent through two coils at this temperature, then separated in the centrifuge with heat on the bowl to produce a refined oil substantially free of soap.

In the above examples, the soap stock was substantially free of entrained neutral oil and also consisted substantially entirely of saponified free fatty acids, such that very little neutral oil was lost in the process.

Thus the process of the present invention involves the employment of low temperatures in order to decrease refining losses. The refining solution is employed in sufficient concentration to substantially immediately break any emulsion.

which tends to form, which thereby decreases the refining loss both because the rate of reaction with neutral oil is decreased when the emulsion is broken and the concentrated refining solution saponifies neutral oil at a lesser rate than more dilute solutions, if separation is effected shortly after mixing. The mixture is maintained for sufficient time only to reduce the color of the oil, and this period of treatment is made as short as possible in order to decrease refining loss. The smaller amount of refining solution which it is possible to use in conjunction with efficient centrifugal separation of the broken emulsion reduces loss due to entrainment of neutral oil. Continuous centrifugal separation of the resulting soap stock from the oil is effected before salting out, so as to avoid stratification in the centrifugal separator, and a heated centrifugal separator is preferably employed to insure continuous discharge of the soap stock from the centrifugal separator. As stated before, if the concentration of the refining reagent necessary to break the emulsion is sufficient to cause stratification in the centrifugal before the necessary color reduction has been effected, a small stream of water may be added to the mixture entering the centrifuge or to the soap stock layer in the centrifugal.

While I have disclosed the preferred embodiments of my invention, it is to be understood that the details thereof may be varied within the scope of the following claims.

I claim:

1. The process of refining animal and vegetable oils containing free fatty acids, which comprises, mixing with said oil at a temperature below 100° F. a proportioned amount of an alkaline refining solution having a concentration between 20 and 50° Bé. and of sufficient concentration to prevent the formation of a stable emulsion at said

temperature, whereby said fatty acids are neutralized and a mixture of oil and soap stock conditioned for centrifugal separation is formed, and thereafter promptly delivering said mixture while at a temperature below 100° F. to a centrifugal separator and centrifugally separating said soap stock from said oil prior to the time at which stratification of said soap stock into a soap layer and nigre layer takes place during said separation.

2. The process of refining animal and vegetable oils containing free fatty acids, which comprises, mixing with said oil at a temperature below 100° F. an alkaline refining solution having a concentration between 20 and 50° Bé. and of sufficient concentration to prevent the formation of a stable emulsion at said temperature, whereby said fatty acids are neutralized and a mixture of oil and soap stock conditioned for centrifugal separation is formed, and thereafter promptly continuously centrifugally separating said soap stock from said oil at substantially the temperature of mixing and while said oil is below a temperature of 100° F., said separation being carried out before sufficient time has elapsed to cause stratification of said soap stock into soap and a liquid fraction in said centrifugal, whereby said soap is substantially cleanly separated from said oil, without substantial entrainment of oil in said soap stock.

3. In the art of refining animal and vegetable oils in which an alkaline refining reagent is mixed with the oil to neutralize said fatty acids and form soap stock and said soap stock is continuously centrifugally separated from said oil, the

improvement which comprises, performing said mixing at a temperature below approximately 100° F., employing a refining reagent having a concentration between 20° and 50° Bé. of sufficient concentration to condition said mixture for centrifugal separation at said temperature, promptly continuously centrifugally separating said soap stock from said oil while said oil is at a temperature below 100° F., and diluting said mixture prior to separation in order to prevent stratification of said soap stock during said separation.

4. The process of refining animal and vegetable oils containing free fatty acids, which comprises, mixing with said oil at a temperature below 100° F. a proportioned amount of a caustic soda solution having a concentration between 20 and 50° Bé. and of sufficient concentration to condition at said temperature the resulting mixture of oil and soap stock for continuous centrifugal separation and thereafter promptly continuously centrifugally separating said soap stock from said oil while said oil is below a temperature of 100° F. prior to the time at which stratification of said soap stock into a soap layer and a nigre layer takes place during said separation.

5. The process of refining animal and vegetable oils containing free fatty acids, which comprises, mixing with said oil at a temperature below 100° F. a proportioned amount of an alkaline refining solution having a concentration between 20° and 50° Bé. and of sufficient concentration to condition the resulting mixture of oil and soap stock for continuous centrifugal separation at said temperature, thereafter promptly continuously centrifugally separating said soap stock from said oil in a centrifugal separator while said oil is at a temperature below 100° F., and simultaneously continuously introducing water into said centrifugal to prevent stratification of said soap stock into a soap layer and a nigre layer due to the concentration of the refining solution.

6. The process of refining animal and vegetable oils containing free fatty acids and coloring materials, which comprises, mixing with said oil at a temperature below 100° F. an excess of a caustic soda solution having a concentration between 20° and 50° Bé. and of sufficient concentration to condition the resulting mixture of oil and soap stock for continuous centrifugal separation, maintaining said mixture in a state of movement at said temperature for sufficient time to substantially reduce the color of said oil, thereafter promptly delivering said mixture to a centrifugal separator while at a temperature below 100° F., continuously centrifugally separating said soap stock from said oil and diluting said mixture prior to separation to prevent stratification of said soap stock into a soap layer and a nigre layer during separation.

7. The process of refining animal and vegetable oils containing free fatty acids and coloring materials, which comprises, mixing at a temperature between 70 and 90° F. an excess of a caustic soda solution having a concentration between 20° and 50° Bé. and of sufficient concentration to condition the resulting mixture of oil and soap stock for continuous centrifugal separation at said temperature, advancing said mixture for sufficient time to effect substantial color reduction of said oil under sufficient conditions of movement to prevent settling of said soap stock from said oil, thereafter promptly continuously centrifugally separating said soap stock from said oil while

- said oil is at a temperature below 100° F., and simultaneously introducing a stream of water into the zone of centrifugal separation to prevent stratification of said soap stock into a soap layer 5 and a nigre layer during said separation, whereby said oil is effectively separated from said soap stock with minimum entrainment of oil in said soap stock.
8. A continuous process of refining animal and 10 vegetable oils, which comprises, mixing at a temperature between approximately 70 and 90° F. proportioned streams of said oil and a caustic soda solution having a concentration between 20° and 50° Bé. and of sufficient concentration to 15 condition the resulting mixture of oil and soap stock for continuous centrifugal separation at said temperature, advancing a stream of the resulting mixture of oil and soap stock toward a centrifugal separator with sufficient movement to prevent settling of said soap stock from said oil 5 while substantial reduction of the color of said oil is effected, and thereafter promptly continuously centrifugally separating said soap stock from said oil in said centrifugal separator at substantially the temperature of mixing prior to the 10 time at which stratification of said soap stock into a soap layer and a nigre layer takes place in said centrifugal separator.

BENJAMIN H. THURMAN. 15
